(57) **CLAIM**

The ornamental design for an injection device, as shown and described.

DESCRIPTION

FIG. 1 is a perspective view of one embodiment of the injection device according to the present invention showing the top, one side and an end.

FIG. 2 is a side elevation of the other side, being a mirror image of the side shown in FIG. 1.

FIG. 3 is an end elevation showing the end visible in FIG. 1.

FIG. 4 is an end elevation showing the end opposite the end shown in FIG. 3.

FIG. 5 is a top plan view of FIG. 1.

FIG. 6 is a bottom plan view of FIG. 1.

FIG. 7 is a perspective view of another embodiment of the injection device according to the present invention showing the top, one side and an end.

FIG. 8 is a side elevation of the other side, being a mirror image of the side shown in FIG. 7.

FIG. 9 is an end elevation showing the end visible in FIG. 7.

FIG. 10 is an end elevation showing the end opposite the end shown in FIG. 9.

FIG. 11 is a top plan view of FIG. 7; and,

FIG. 12 is a bottom plan view of FIG. 7.

The broken line portions of the drawings are for illustrative purposes only and form no part of the claimed design.
